UNITED STATES PATENT OFFICE.

KARL G. SOMMER, OF BATTLE CREEK, MICHIGAN, ASSIGNOR TO AMERICAN STEAM PUMP COMPANY, OF BATTLE CREEK, MICHIGAN, A CORPORATION OF MICHIGAN.

CENTRIFUGAL VACUUM PUMP.

Application filed March 23, 1925. Serial No. 17,632.

This invention is an improvement in so called centrifugal vacuum pumps, and its principal object is to provide a pump simple in construction, efficient and economical in operation, and capable of drawing in a large amount of air or producing high suction without consuming a great deal of power. A further object is to provide a centrifugal vacuum pump which is positive in its action, will deliver large volumes of air without pulsation, and which will be absolutely reliable. A still further object is to provide a centrifugal vacuum pump whose efficiency will be maintained for an indefinite period, and which can be driven by a high speed electric motor or any suitable device.

In the accompanying drawings, I have illustrated one practical form of pump embodying the invention, and one practical use thereof; and I will explain the invention with reference thereto, and summarize in the claims the essentials of the invention, the novel features of construction, and novel combinations of parts, for all of which protection is desired.

In said drawings:

Figure 1 is a vertical section through the pump on the line 1—1, Figure 2.

Figure 2 is an enlarged transverse vertical longitudinal section through the pump on the line 2—2, Figure 1.

Figure 3 is an enlarged horizontal longitudinal section through the pump on the line 3—3, Figure 1.

Figure 4 is a detail vertical section through one of the side castings or heads of the pump on the line 4—4, Figure 6.

Figure 5 is an enlarged vertical section through the rotor detached.

Figure 6 is an outer side view of one of the side castings or head of the pump.

Figure 7 is an outer view of the opposite side casting or head of the pump.

As shown in the drawing, the pump comprises a casing 1, and a rotor or runner 3 mounted on a shaft S, the runner and shaft being the only moving or rotating parts.

The casing 1 comprises a body casting 1^a and opposite castings or heads 2 securely fitted and attached to opposite sides of the body casting 1^a. The casting 1^a has an approximately central cylindric chamber, in which is fitted the rotor or impeller 3 and

is provided exterior to the rotor with a volute passage 1^b extending about half way around the rotor and communicating with a water discharge passage 1^c in an upward extension of the body casting. Above the rotor 3 and opposite the volute chamber 1^b, in the body casting, is a smaller air and water chamber 1^d which communicates with a passage 1^e. The body casting also has a port 1^f at one end which communicates with passages 2^a in the side castings or heads 2, hereinafter referred to; and the body casting also has a port 1^g diametrically opposite the port 1^f, which communicates with passages 2^b in the heads 2, as hereinafter explained. The chamber 1^b is preferably volute, and increases gradually in cross section from inlet toward the outlet thereof.

The heads 2 are preferably of cast metal, preferably of the form shown in Figures 2, 3, 4, 6 and 7, and are provided with passages 2^a communicating with the inner ends of passages 3^b of the rotor 3, and passages 2^b communicating with the port 1^g and the passages 3^b of the rotor, as indicated in Figures 2 and 3. The heads are bolted to the body casing 1 and thus the chambers 1^b, 1^d are tightly closed, except for the ports. Each head is provided with a central hub portion 2^c in which the shaft S is journaled, and is also provided with suitable stuffing boxes in which the packing is held in the usual manner, by means of glands 2^d.

The passages 2^a, 2^b in each side casting 2 extend from opposite ends thereof but do not communicate with each other, as more clearly indicated in Figures 6 and 7. The passages 2^a, 2^b are divided by a wall 2^e as shown, there being no communication therebetween, each being independent of the other. The hub portions 2^c of the opposed heads 2 are stationary and fit closely into annular recesses 3^a in the rotor or impeller 3 as shown in Figures 2, 3 and 5.

The rotor or impeller 3 is fixedly secured on the shaft S so that it rotates therewith, and is preferably made of bronze, and has opposite recesses 3^a in its hub into which enter the hub portions 2^c of the heads 2 as shown. The rotor shown is of the double suction type, air and water entering on both sides. The rotor has parallel sides and its side surfaces run close to the opposed surfaces of the heads 2, which close the ends

of the central chamber in the body casting as shown. In the walls of the rotor are a series of curved passages 3^b which extend from the periphery of the recess 3^a in the 5 rotor to the outer periphery of the rotor. The series of small passages 3^b are open at each end. Each passage 3^b is preferably of equal diameter or cross section throughout, this being desirable to enable the water to 10 push or pull out the air effectively. The passages 3^b, at their inner ends communicate with the ports or passages 2^a and 2^b through ports 2^a and 2^b respectively in the hub portions 2^t of the heads 2. 15 As shown in Figure 1, the passage 3^{bx} of the rotor 3 is just beginning to communicate with the passage 2^b, and the diametrically opposite passage 3^{bz} is just communicating with the passage 2^a, and if the rotor is operated at high speed air will be discharged 20 through the duct 1^e, and air and water will be discharged through passage 1^c. The size and number of the passages in the rotor may be varied according to the suction pressure 25 desired to be maintained in the pump, and the size of the pump.

It will be seen from the drawing that the rotor is located eccentrically of the volute water chamber 1^b, said chamber preferably 30 gradually increasing in cross section, anti-clockwise around the rotor, from its inlet to outlet. The passages 3^b in the rotor are preferably curved in the direction in which the rotor rotates as shown. The rotor is 35 divided or separated in the hub portion by a wall or bridge, and the only communication of the passages 2^a, 2^b with passages 3^b is through the ports 2^a and 2^b.

When the rotor is running air and water 40 is drawn in through the ports 2^s and 2^t, water entering at 2^s and air condenses entering at 2^t. The air is drawn into passages 3^b when they connect with port 2^s; beyond this port, the centrifugal pressure 45 of the water forces out the air into the air and water chamber 1^d; and during the further rotation of the rotor water is drawn in from passage 2^a through port 2^s and discharged into chamber 1^b. Thus due to rotation and change of positions of the passage 50 3^b in relation to the ports 2^s and 2^t, air will be pushed out by the water into chamber 1^d under influence of centrifugal force; and large volumes of air can be handled with a 55 very small volume of water. The passages 3^b should be uniform in cross sectional area throughout for most effective results.

The water enters the rotor at a low pressure or velocity and is accelerated into the 60 volute chamber for delivery. The air and water is separated in the volute chamber 1^b the air leaving at the top entering the passages 3^b. At the top of the volute chamber and near the outlet end thereof is a wide

wall 1^h in the body casting 1, which wall makes a close fit with the periphery of the rotor. The centrifugal force of the water circulated in pump and rotor causes the drawing in of the air and also the expulsion of same. The water is removed from the inlet to the outlet by the operation of the 70 rotor, which being preferably double, causes such a suction when rotating as will effectively draw in air through the inlet ports and discharge same through the outlet ports. 75 The air is admitted on each side of the rotor and a very large volume of air can be delivered at a low vacuum.

The rotor is hydraulically balanced, and there is no end thrust to interfere with high efficiency and proper operation. The air is delivered through the rotor passages at the highest portion of the pump, and the air travels upward and not downward, thus insuring greater volumetric efficiency. No air 85 is allowed to travel up through the rotor from the periphery at the bottom.

The described combination and arrangement of parts makes an efficient vacuum pump, which is positive in action and will 90 exhaust a very large volume of air and deliver it without pulsation. Such pump is absolutely reliable and its efficiency will be maintained for an indefinite period as the rotor and shaft are the only rotating parts. 95 The pump will stand up for a long time because of the few moving parts, and the torque required to operate the pump is very low, as it is only necessary to overcome the inertia of the rotor and shaft which are the 100 only moving parts. There are no close running fits which are liable to give trouble.

In the drawings, (Figures 1 to 3) the pump is shown as arranged for use as a centrifugal boiler-feed pump. In this case the air inlet 1^e of the pump is connected to the heating system from which air and condensate is to be drawn by means of a check valve P and globe valve R. The pump water inlet 1^f is also connected to a receiver 110 R' from which water is supplied to the pump. Air is discharged from the pump into the receiver R' through the passage 1^c which is connected therewith. The receiver is open to the atmosphere. The discharge 115 port 1^c of the pump is connected to the boiler by a fitting H which should be provided with a suitable check valve N and globe valve O. The fitting H is connected with the receiver R' by a pipe I, in which is 120 a valve J, operatively connected with a float in the receiver R', so that the valve J will be closed if the water in the receiver runs above a predetermined level.

When the rotor is operated it draws in air 125 and water and while the water in the receiver is low the pump discharges air and water through 1^e, and water at 1^c, which

water circulates through pipe I and valve J into receiver R'. While this is being done air and water is drawn in at inlet 1^g which is connected with the heating returns; while 5 water is drawn through inlet 1^f into the pump. Thus there is a continuous pump action from 1^f and 1^g to receiver through 1^e and 1^c and valve J.

As the water and condensate is drawn in- 10 to pump and discharged into the receiver the water will gradually accumulate and rise in the receiver until it raises the float which tends to close valve J which is connected with the float rod, and when the dis- 15 charge water cannot pass through the valve J the water is discharged through check valve N to the boiler, as the water, follow- 20 ing the line of least resistance then goes to the boiler. The float is so arranged that the water in the receiver will not be lowered 25 below the top of inlet 1^f. When the water is discharged to the boiler the water lowers in the receiver R' permitting the float to gradually open the valve J, and allows 30 the water to circulate back into the receiver; and when the float is in such position, due to the level of the water in the receiver, that the valve J is fully open, the water instead of going to the boiler through check valve 35 N takes the line of least resistance and dis- 40 charges back into the receiver. The receiver is always open to the atmosphere and as air and water is separate in the pump no air is delivered to the boiler. The air is deliv- 45 ered to chamber 1^d at top of pump, and wa- 50 ter is delivered only to the bottom of pump at 1^c. If air was delivered at bottom of pump it would tend to pass to the delivery passage 1^c but since air is delivered only at 55 top the air continues to flow upward.

In the normal working condition of the apparatus water will stand in the receiver R' and casing at least to the level of the top of the inlet 1^f, so that the channels 3^h 60 in the rotor and the chamber 1^b will be nor- 65 mally filled with water. Back flow of wa- 70 ter to the port 1^g is prevented by the wall 2^e. When the rotor (Figure 1) is rotated anti-clockwise the water contained in the 75 passages 3^b is thrown outward by centrifugal force into chamber 1^b. The water is drawn into the passages 3^b through the ports 2^a 80 communicating with passages 2^a and thence expelled through the passages 3^b into the chamber 1^b, and any surplus water enter- 85 ing this chamber 1^b will pass through the passage 1^c, fitting H, and pipe I, back into the receiver R if the valve J be open; but if the valve J be closed such water will be 90 discharged to the boiler through the check valve N. The action of the rotor, however, creates a suction in the passages 2^b and air and condensate is drawn from the system R through the port 2^t and passages 2^b and 95 this air and condensate is discharged 100

through the rotor passages 3^b into the air and water chamber 1^d and conducted by pipe 1^e into the receiver R'.

As stated, during the rotation of the rotor the water drawn into the passages 3^b through port 2^s will be expelled by centrifugal force into the chamber 1^b and air will take the place of the displaced water. The outer ends of the passages 3^b are closed when the passages pass the lower end of the wall 1^h, see Figure 1, but the passages 3^b will fill with air or condensate drawn in through the ports 2^t from passages 2^b. After passing the wall 1^h the air and condensate will be discharged into the air and water chamber 1^d; communication between the latter chamber and the chamber 1^b being prevented by the wall 1^l opposite wall 1^h, with which the rotor has a close running fit. The passages 3^b again become filled with water when 85 their inner ends register with port 2^s; and the above described operations are repeated during the rotation of the rotor.

The novel centrifugal vacuum pump can be arranged for continuous operation, or automatic operation. If the pump is driven by electric motor a vacuum regulator should be installed in the line leading to 1^g and connected with a suitable self starter, this method will allow the motor to stop at high vacuum and start at low vacuum. The pump is arranged for motor drive, belt drive, or turbine drive, as preferred.

What I claim is:

1. In a centrifugal vacuum pump or compressor a casing having a rotor chamber, a water outlet, an air outlet, a water inlet and an air inlet; a shaft extending through said chamber; and a rotor mounted on said shaft within said chamber, and having passages 100 open at both inner and outer ends and adapted to alternately register with the water inlet and air inlet in each revolution of the rotor.

2. In a pump as set forth in claim 1, 110 means for supplying water to the rotor chamber to enable the rotor to discharge air from the passage by the water under the action of centrifugal force.

3. A centrifugal vacuum pump as set forth in claim 1 having the discharge of air 115 at the top of the rotor.

4. A centrifugal vacuum pump comprising a casing having a chamber for reception of a rotor, a water discharge chamber adjacent said rotor chamber an air and water chamber adjacent the cylinder chamber, a water inlet; a condensate inlet; a rotor rotatably mounted in said rotor chamber and having radially disposed passages open at 120 their inner and outer ends, the inner ends of said passages registering alternately with the said inlets as the rotor rotates, and the outer ends of said passages alternately communicating with the water discharge chamber 125 130

ber and with the air and water chamber as the rotor rotates.

5. In a pump as set forth in claim 4, means for supplying water to the rotor chamber to enable the rotor to discharge air from the passages by the water under the action of centrifugal force.

6. A centrifugal vacuum pump as set forth in claim 4, having the discharge of air at 10 the top of the rotor.

7. A centrifugal pump comprising a casing having a chamber for reception of a rotor, a water discharge chamber at one side of said rotor chamber communicating with 15 a water discharge passage, an air and water chamber opposite the first chamber communicating with another discharge passage; a water inlet to the casing, a condensate inlet to the casing, and ports communicating with 20 said water and condensate inlets; a rotor rotatably mounted in said rotor chamber and having radially disposed passages open at their inner and outer ends, the inner ends of 25 said rotor passages registering alternately with the said ports as the rotor rotates and the outer ends of said rotor passages alternately communicating with the water discharge chamber and with the air and water chamber as the rotor rotates.

8. In a pump as set forth in claim 7 means for supplying water to the rotor chamber to enable the rotor to discharge air from the passages by the water under the action of centrifugal force.

9. In a centrifugal vacuum pump as set forth in claim 7, having the discharge of air at 30 the top of the rotor.

10. A centrifugal vacuum pump comprising a casing having a chamber for reception of a rotor, a water discharge chamber adjacent 40 said rotor chamber, an air and water discharge chamber adjacent the rotor chamber, a water inlet, a condensate inlet, passages in the casing respectively leading from the water inlet and the condensate inlet to opposite sides of the center of the said rotor chamber and radially disposed ports for said 45 passages extending to points located within the hub of the rotor; a rotor rotatably mounted in said rotor chamber and having radially disposed passages open at both their inner and outer ends, the inner ends of said 50 passages being adapted to alternately register with the said ports, and the outer ends of

said channels being adapted to alternately communicate with the water discharge chamber and with the air and water discharge chamber as the rotor rotates.

11. In a pump as set forth in claim 10, means for supplying water to the rotor chamber to enable the rotor to discharge air from the passages by the water under the action of centrifugal force.

12. A centrifugal vacuum pump as set forth in claim 10, having the discharge of 65 air at the top of rotor.

13. A centrifugal pump of the character specified comprising a body member having a cylindric chamber for a rotor, a volute chamber at one side of the cylindric chamber 70 communicating with a water discharge passage at its larger end, an air and water chamber at the side of the cylindric chamber opposite the volute chamber and communicating with an air and water discharge 75 passage; a water inlet, and a condensate inlet; a pair of heads attached to the body member and closing the sides of the said cylindric chamber said heads having inwardly projecting hub like portions provided with ports on their outer peripheries and with passages respectively connecting the said ports with the water inlet and with the condensate inlet of the body member; a rotor mounted in said cylindric chamber and having annular recesses on its opposite sides to receive the inwardly projecting hub like portions of the heads said rotor having a plurality of radial passages open at both 80 their inner and outer ends, the inner ends of said rotor passages being adapted to alternately register with the inlet ports and the outlet ports in the hub portions of said heads as the rotor rotates, and the outer ends of said passages alternately communicating 85 with the volute chamber and with the air and water chamber as the rotor rotates.

14. In a pump as set forth in claim 13, means for supplying water to the rotor chamber to enable the rotor to discharge air from 100 the passages by the water under the action of centrifugal force.

15. A centrifugal vacuum pump as set forth in claim 13 having the discharge of air at 105 the top of the rotor.

In testimony that I claim the foregoing as my own, I affix my signature.

KARL G. SOMMER.
